UNITED STATES PATENT OFFICE

WILLIAM M. POST, OF HOOD RIVER, OREGON

COMBINATION DENTURE PRESS AND VULCANIZER

Application filed October 17, 1929. Serial No. 400,345.

This invention relates to an improved dental machine of the type generally known in the profession and trade as a combined denture press and vulcanizer.

5 Briefly stated, the structure is characterized by a leg supported steam tight container having a removable cover, appropriate gauge means and pressure release means.

The principal improvement is predicated upon a removably internally arranged denture press which depends for its clamping action on a vertically liftable flask carrying cradle and cooperable details for insuring a positive and gradual compressing and

15 marginal portion of the removable cover 13.

The cover has a central upstanding sleeve 14 provided on its upper end with a stuffing box 15. An operating stem or shaft 16 is threaded through the sleeve and down into the interior of the container. It is provided on its upper end with operating handles 17. On the lower or inner end is a retaining collar 18 carrying a ball race structure 19 for reducing friction. The ball race engages with the top plate 20 of the internal cradle structure and the shaft 16 passes through a plain hole in the plate 20, said hole being of greater diameter than the diameter of the shaft. Thus the plate is swiveled to the shaft. The top plate is connected with a base or bottom plate 21 by way of bolts 22, there being a series of four of these bolts arranged as seen in Figure 5.

20 The bottom plate is provided on opposite sides with outstanding apertured projections 24 receiving the lower reduced end portions of the pair of diametrically opposite retaining strips 25. The upper ends of these strips are also reduced as at 26 and extend through apertures in the outstanding projections 27 formed on the bottom of a part generally referred to as a bumper 28. This bumper is provided with extension arms 29 having outstanding flanges 30 at their upper ends detachably engaged with keepers 31 formed on the underside of the cover 13, as seen plainly in Figure 2. Set screws 32 are provided for assuring proper connection to the bumper.

25 Figure 5 is a similar cross section on the line 5—5 through the cradle looking downwardly.

The bumper also includes a U-shaped portion 33 at its bottom, and it will be noted that the top plate 20 is rectangular and of an area to telescope into the bumper and to allow the flasks 34 and 35 to come into clamping engagement with the U-shaped member 33.

Figure 6 is a detail sectional view of one of the retainers constituting a part of the

30 flask carrying cradle.

Referring now to the drawings in detail, and specifically to Figure 2, it will be observed that the reference character 7 designates the casing which is in the nature of a fluid tight container and provided with appropriate supporting legs 8. Carried by an annulus 9 at the top are outstanding ears 10 which carry pivotally mounted threaded retainers or fastening devices 11 which cooperate with spaced clamping lugs 12 on the

35 On the cover plate is a hand controlled pressure relief cock 36, a pressure gauge 37 and an automatic blow-off valve 38.

40 Place the flask in the cradle with teeth in lower side of flasks. Put sufficient amount of water to cover top flask two inches or more. Never fill pot full. Allow thirty-five (35) minutes to raise seventeen (17) pounds steam pressure. Turn shaft 16 back.

100

ward every three minutes. The required time to press a case is from twelve to fifteen minutes. Allow steam gauge to return to zero. Open relief valve and remove cradle. Allow 5 case to cool three hours. Do not release cradle until case has cooled. To release cradle return same to the pot 7 and set cover tight. Turn shaft downward to release flask. This will save time and trouble. Finish the 10 case with files and scrapers. Do not use emery cones as they heat the plate, distorting the same.

When pressing only one case put flask in the bottom of the cradle and empty flask on 15 top. Cover lower flask with two inches of water. The case is pressed when the top plate comes to a stop. Do not turn shaft after coming to the stopping point. Cut off surplus material from sides of the flasks to 20 insure easy removal from the cradle.

Do not open relief valve to reduce temperature. Allow same to cool before opening pot. After plate is finished treat with ammonia. One teaspoonful ammonia to one cup water 25 in fruit jar. Screw cover on tight and allow case to remain in jar overnight.

Remove the cradle, close valve below safety valve. Four vulcanite cases may be vulcanized at one time by using flask clamps. Place 30 crosswise in the pot, raise the pressure to one hundred pounds in forty-five minutes and hold for fifty-five minutes. Allow steam gauge to return to zero before opening vulcanizer. Open petcock before removing cover, to allow the air to escape. The pot should 35 be cleaned after using. Finish case in the usual manner.

For running up models and investing cases a good grade of flasking plaster is recommended. Mix the plaster thoroughly with 40 the fingers so that dry spots and lumps will not occur. Be sure that the upper and lower parts of flask are in complete contact on edges before pouring upper part of flask. Allow 45 plaster to set three hours or more before boiling out the wax. The pressing should be done at once. If allowed to stand the plaster will deteriorate causing misplacement of the teeth. Do not remove any plaster that has 50 run between flask sections. Cut waste gates as shown in flask. Plates with anterior undercuts should be invested high in front part of flask. All undercuts in the part of flask containing the teeth should be cut away. 55 This will avoid folding out of the blank.

To regulate the cradle: Turn cradle against cover or lid. Place flask in position and tighten the four nuts until flask is held tight in place. Always test cradle before pressing. 60 Be careful not to hit rim of pot with cradle. When removing cured plates from flask do not use a steel hammer. Allow escape valve to remain open until considerable live steam has escaped. This will insure correct regulation. Any air left in vulcanizer causes in-

correct regulating. Keep pumice very wet when finishing and use as little pressure on buff wheel as possible. This will prevent warping of plate. If blanks do not fit models, place in hot water. Do not boil. Press 70 into place with fingers.

From the foregoing description and drawings it will be seen that I have evolved and produced a simple and economical type of press and vulcanizer wherein the principal novelty is in the construction of the press which is characterized by a vertically liftable cradle, said cradle being such in construction and operation as to fulfill the requirements of a structure of this class in a more satisfactory, dependable, and efficient manner. It is thought that persons skilled in the art to which the invention relates will be able to obtain a clear understanding of the construction, operation, and features and advantages 85 after considering the description and the accompanying drawings. Therefore a more lengthy description is regarded as unnecessary.

Minor changes in shape, size, and materials 90 and rearrangements of details coming within the field of invention claimed may be resorted to in actual practice if desired.

I claim:

A press of the class described comprising: 95 a cylinder, a detachable cover for the cylinder, a substantially U-shaped bumper member having upwardly extending legs, means for detachably connecting the upper ends of the legs to the under side of the cover, a top 100 plate shaped to pass through the U-shaped member, a bottom plate, bolts connecting the plates together in spaced relation, a pair of strips having their lower ends resting on the bottom plate one at each side thereof, perforated ears extending outwardly from the bumper member and the strips having reduced upper ends sliding thru the perforations, a threaded stem passing through a 105 threaded part of the cover and swiveled to the top plate whereby turning movement of the stem will move the holder which includes the upper and lower plates.

In testimony whereof I affix my signature.

WILLIAM M. POST.
